CLAIM

The ornamental design for a smart meter protection device, as shown and described.

DESCRIPTION

FIG. 1 is a perspective view of a smart meter protection device shown;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a bottom plan view thereof;

FIG. 7 is a top plan view thereof; and,

FIG. 8 is another top plan view of the smart meter protection device and shows the smart meter protection device applied over a smart meter.

Any broken lines shown in FIGS. 1-8 are included for the purpose of illustrating environmental elements only and form no part of the claimed design.

1 Claim, 4 Drawing Sheets
